Lewis E. Webster

BY Kerr Pay, Cooper & Hayward

ATTORNEY

UNITED STATES PATENT OFFICE.

LEWIS E. WEBSTER, OF WYOMING, PENNSYLVANIA.

SHOVEL HANDLE.

Application filed October 17, 1921. Serial No. 508,242.

To all whom it may concern:

Be it known that I, LEWIS E. WEBSTER, a citizen of the United States of America, residing at Wyoming, in the county of 5 Luzerne and State of Pennsylvania, have invented certain new and useful Improvements in Shovel Handles, of which the following is a full, clear, and exact description.

This invention relates to improvements in 10 shovel handles and more particularly to shovel handles of D type formed from sheet metal.

In the shovel making art it has been the practise to form the D handle of the shovel 15 from wood, preferably well seasoned ash. The configuration of the D handle is such that there is considerable waste of wood in the process of forming these handles, and much labor is required in forming them.

It is one of the objects of my invention to 20 provide a sheet metal handle which will cut down the waste of this wood and also reduce the cost of the handle.

Previous attempts have been made to provide 25 metallic handles for shovels and like tools. These former handles have not been satisfactory inasmuch as they had certain characteristics which distinguished them from the usual wooden D handle. Among 30 these may be mentioned the difference in weight and contour, the provision of an open flanged construction for the side arms of the D handle, the use of metallic grips which chill the laborers' hands in cold 35 weather and rotation of the grip relatively to the body portion of the handle. This latter characteristic is particularly objectionable to shovel users since it largely diminishes the "purchase" or leverage which 40 the laborer can secure upon the shovel over that which he can secure with the solid wooden D handle having a unitary grip portion.

It is among the objects of the present invention to provide a shovel handle of sheet metal which will retain the desired and well known characteristics of the solid wooden D handle so as to be equally satisfactory to the user.

Other objects reside in the provision of a 50 sheet metal shovel handle which will be simple, inexpensive to manufacture and assemble and which will stand up under severe usage.

Other objects of the present invention 55 reside in the provision of a handle which provides an extended bearing for the wood shank portion, whereby rocking or tilting of the shank in the handle is prevented.

Another object of the present invention 60 resides in the provision of depressed portions in the flat portion of the D handle, thereby strengthening and reinforcing the flat portion of the handle and rendering the same less liable to deformation when in 65 use. The edges of these depressions also cooperate to form shank receiving shoulders.

Another object of the present invention resides in the provisions of a sheet metal 70 handle receiving element of such contour that the same can be readily assembled with the main sheet metal body portion. This handle receiving element materially reduces the cost of manufacturing the main portion of the handle and simplifies the assembly 75 of the entire handle.

In the drawings:

Fig. 1 shows an assembly view of a preferred embodiment of my invention.

Fig. 2 is a detail sectional view taken on 80 line 2—2 of Fig. 1.

Figs. 3 and 4 are sectional views taken on lines 3—3 and 4—4 respectively.

Figs. 5 and 6 are front and side views of the handle receiving element.

Fig. 7 shows a front view of the main body portion prior to the assembly of the handle receiving element therewith and prior to the bending in of the flange portion.

Fig. 8 is a side view of the part shown in 90 Fig. 7.

Fig. 9 is a front view of a modified type of handle with a short flat portion and with a tamping grip.

Fig. 10 is a side view of the handle shown 95 in Fig. 9.

As shown in the drawing, 10 designates the tubular seamless shank which is open at the bottom to receive the wooden shank 11. Integral with the shank and extending 100 upwardly therefrom, the sheet metal is extended to form the flat portion 12, which corresponds in general contour to the corresponding part of the D handle. The flat portion is of hollow box section, as shown 105 in Fig. 2, and is preferably provided with indented portions 13 which add rigidity to the otherwise plate like metal "flat" portion

of the handle. Intermediate these indented portions the metal is shaped, as shown at 14, to provide an extended socket for the wooden shank. The shank may be fastened 5 to the handle by two rivets 15^a which extend through suitable holes in the shank portion 10 and the extended shank socket portion 14.

Extending upwardly and integral with the flat portion are the spaced arms or 10 prongs 15. These parts initially are of hollow channel section and are provided with a curved recess 16 (Fig. 7) to receive the round grip receiving portion of the handle. They are also rounded, as shown at 17, to 15 conform to the curvature of the grip when bent inwardly.

The grip receiving element is best shown in Figs. 5 and 6. This element is formed of one integral U-shaped piece of metal comprising a flat strip of metal 18 with curved flanges 19 upon the outer edges thereof. (See Fig. 4.) At the upper ends, the strips 18 are shaped to form cups 20 having indented bosses 20^a therein. These portions 25 receive the wooden grip 21, and the latter is preferably turned with the grain of the wood running lengthwise, thereby obviating splitting. The grip may be held tightly in place in any desired manner as by the slotless screws 22 which form the subject matter of 30 a separate application. It will be understood that, in assembling, the grip in place, the grip receiving element is first sprung to allow the grip to be inserted in the cups. 35 Then, after the U arms have been brought together to embrace the grip in cups 20-20^a, the slotless screws are driven in and when in place prevent the turning of the grip relatively to the grip receiving element.

40 After the wooden grip is properly secured in place, the grip receiving metal piece or element is inserted in the open top of the main body portion, fitting closely in the interior of forked arms 15. Thereafter the edges of the arms 15 are rolled over, as 45 shown at 23 in Figs. 2 and 4, to thereby closely embrace the edges 19 of the grip receiving element 18. These edges, together with the flat strip 18, form the closure wall 50 for the interior of the D opening. When the edges are thus rolled over the cut-away arc portions 17 closely conform to the contour of the wooden grip.

The handle is now complete and ready to 55 be assembled upon the shank. This is done by boring the shank and riveting in the manner previously explained. Proper alignment of the shovel blade and the handle may be readily obtained by proper alignment of 60 the holes, and no bending of the metal arms is necessary.

The completed handle is of pleasing contour conforming almost exactly to the well known wooden D handles. The extended 65 socket construction obviates shake, and the

use of the separate grip receiving element materially reduces the cost of pressing and drawing of the sheet metal parts. The grip receiving element is of proper dimensions to snugly fit the main handle body and after 70 the edges 23 are turned over the completed handle is, in effect, a unitary article with a closed smooth wall entirely around the D opening.

The modified type shown in Figs. 9 and 10. 75 is substantially the same except that the flat portion 12 is shorter and the grip 21^a is substantially oval in cross-section. In this form the grip is retained in place by a through rivet 22^a. The cup portion 20 is 80 likewise oval.

Certain features of the present invention are claimed in my copending applications Serial No. 542,929, filed March 11, 1922, and Serial No. 433,257, filed December 27, 1920. 85

What I claim is:

1. A sheet metal shovel handle, comprising a hollow body portion including a pair of spaced arm portions of hollow channel section, a shank portion integral with said body portion, said body portion having substantially flat portions and shaped to form an extended socket for the inserted shank. 90

2. A sheet metal shovel handle, comprising a hollow body portion having an integral downwardly extending open shank portion, said body portion having the substantially flat portions thereof shaped to form an extended socket for the inserted shank, said socket extending upwardly from 100 the point of junction of the body portion and said first mentioned shank portion.

3. A sheet metal shovel handle, comprising a hollow body portion having integral channel-like arm portions, an independent 105 grip receiving element fitted within said arm portions and embraced thereby, and a grip carried by integral cup members on said element.

4. A sheet metal shovel handle, comprising a hollow body portion provided with an integral shank portion and a pair of spaced arm portions, a grip receiving element including integral cup-like members on the upper ends thereof, said element being fitted 115 in and embraced by turned over edges of said arm portions, and a grip carried by said element.

5. A sheet metal shovel handle, comprising a drawn body portion having an open 120 top and open shank portion, said body portion having a flat portion indented to reinforce the same and form an extended socket portion for the inserted shank.

6. A sheet metal shovel handle, comprising a sheet metal hollow body portion, and a separate grip receiving element formed of a unitary piece of sheet metal connected to the body portion, said element having 125 flanged portions embracing the grip, said 130

body portion and element having coacting inturned edges to engage each other and secure the parts together.

7. A shovel handle comprising a sheet metal U-shaped grip receiving portion separate from the body portion of the handle and having cooperating flanged and cupped portions to receive the grip, and having in-turned flanged edges upon the arms of the element for the purpose described.

8. A sheet metal shovel handle, comprising a grip portion, a hollow sheet metal body portion, a separate sheet metal grip receiving portion, said body portion having

the edges thereof turned in to embrace and secure the grip receiving portion thereto, said grip receiving portion having coacting inturned edges to fit the body portion.

9. A sheet metal shovel handle, comprising a hollow sheet metal body portion and a separate grip receiving portion embraced thereby, a grip carried thereby, and means cooperating with the grip and grip receiving portion for preventing relative rotation of said grip.

In testimony whereof I hereto affix my signature.

LEWIS E. WEBSTER.
